UNITED STATES PATENT OFFICE

DANIEL S. HOLT, OF NEW BRUNSWICK, NEW JERSEY, ASSIGNOR TO ARMSTRONG CORK COMPANY, OF LANCASTER, PENNSYLVANIA, A CORPORATION OF PENNSYLVANIA

BLOCK-PRINTING MACHINE AND METHOD OF OPERATING THE SAME

Application filed September 23, 1927. Serial No. 221,449.

This invention relates to printing machines, and particularly to printing machines of the reciprocating block type commonly employed in the printing of floor coverings 5 such as linoleum and felt base goods.

Machines of this type are shown in United States Patents No. 492,902 to Deinelt and Eisenhardt dated March 7, 1893, and No. 1,159,801 to Waldron dated November 2, 10 1915. A machine of this general type is also shown in Patent No. 1,263,900 to Jones and Webster dated April 23, 1918.

Printing machines of this general type are provided with a plurality of reciprocating heads, each of which carries a printing block. 15 The number of heads which are used depends on the number of colors which appear in the printed pattern as well as the design of the pattern itself. In the printing of rugs, for 20 instance, there is one set of heads which have complementary printing blocks thereon for reproducing the field pattern of the rug and side borders. There is another set of blocks for printing the various colors in the cross 25 borders. The rugs are printed on a strip of either definite or indefinite length which is progressively moved through the machine under the various printing heads. Rugs which are printed on felt base goods are, ac- 30 cording to usual practice, printed on strips of different lengths, usually from 121 to 123 feet long. In the printing of linoleum the strip of linoleum is usually much longer and the length varies considerably, the linoleum 35 being fed through the printing machine practically continuously.

In the printing of piece goods as distinguished from rugs, the number of printing heads which are necessary is usually less, be- 40 cause there are no cross borders to be printed.

In the printing of both rugs and piece goods, it is necessary that the printing heads be operated in a predetermined relation so that the proper colors and proper patterns 45 will be printed on the strip of goods at the proper time.

According to the present invention there is provided a novel trip control for printing heads in a machine of this type wherein the 50 selective operation of the printing heads is

secured. The selector mechanism is of an extremely simple construction and one which provides a high degree of flexibility. The invention further proposes the provision of an automatic master controller for the selector 55 mechanism arranged to secure the proper sequence of movement of the printing heads for a given pattern so that manual adjustment of the different selector contacts when a different pattern is to be made is not necessary. 60

In the ordinary block printing machine the blocks are coextensive with the width of the material being printed, and the width of the blocks is ordinarily 18 inches, so that each 65 block is capable of printing entirely across the width of the strip, but will only cover an 18-inch section in the length of the strip. The printing heads are also ordinarily spaced 36 inches apart from center to center, so that 70 between adjacent heads there is a space of 18 inches. In the operation of the machine the material is moved under the heads progressively 18 inches at a time. For the purpose of the present invention it is therefore convenient to image the material being printed on as consisting of a series of contiguous 18- 75 inch sections.

Each head of the printing machine is provided with a separate electrical control mechanism, and a selector is provided having a series of contacts for each control. A movable carrier is embodied in the selector which has a plurality of shiftable contacts thereon. In the printing of a piece of material of defi- 80 nite length the carrier has a shiftable element for substantially each 18-inch section in the entire length of the piece. The carrier is progressed through the selector proportionately to the movement of the piece of 85 goods through the printing machine, and each of these shiftable contact members is adjusted to a position where it will control, in its movement through the selector, those printing heads which are to print on the par- 90 ticular 18-inch section of material controlled by it. This secures an extremely flexible trip control. For instance, if in the printing of rugs 12 feet in length, the length of the 95 piece is not sufficient to give an even number 100

of 12-foot rugs, then the sequence of movement of the printing heads can be easily shifted to print a shorter rug at some point in the length of the strip. Likewise, if a defect appears in the material being printed, the sequence of operation can be interrupted so as to prevent the printing of any pattern on the defective material, and if rugs are being printed, one rug can be finished off before the defect is reached. Shiftable contactors controlling the 18-inch section or sections in which the defect appears can be moved to an inoperative position so no printing will occur on the defective spot. The printing of the next rug can be started immediately behind the defect in the material. With this arrangement considerable material is saved because base material with defects therein does not need to be printed but can be skipped and because, in the printing of rugs, shorter rugs can be printed on uneven lengths.

While the shiftable contacts can be adjusted manually to obtain the desired sequence in the movement of the printing heads, there are a relatively large number of these shiftable contacts and it is therefore desirable to have a master controller which will automatically shift the movable contacts to the desired position, but which will not impair the flexible manner in which the selector may be operated. According to the present invention such a master controller is provided.

The invention may be understood by reference to the accompanying drawings which illustrate an embodiment of my invention, but it will be understood that the drawings are merely illustrative and that the invention is not confined to the particular construction and arrangement of parts therein shown.

Referring to Figure 1, 2 designates the frame of a printing machine which may, for instance, be of the type shown in Waldron Patent No. 1,159,301 above referred to. The frame of the machine supports a bed 3 over

which the material to be printed is intermittently moved by suitable mechanism not shown, but of any type well known in the art.

Arranged over the bed of the machine are a plurality of printing heads 5. Each of

these printing heads, or those which are to be used in the printing of a given pattern, is provided with a printing block 6. Color

carriages are provided for each printing block, all of these color carriages being designated 7. They are all connected together for simultaneous reciprocal movement. In

operation a carriage passes from one side of the head to which it supplies color to the other and in so doing applies paint to the printing surface of the block. The mechanism is so arranged that the blocks can only

come down to print on material on the bed of the machine after the carriages have been moved to a position at one side of the head.

In Figure 1, the color carriages are shown directly under the printing blocks, but in

operation they are only momentarily in this position.

For operating the printing heads, each head is provided with an operating shaft 8. The shafts 8 are all operated in unison from a single driving mechanism located at 9, the driving connections not being shown in the diagram in Figure 1 and forming no part of the present invention. On each end of each cross shaft is a cam 10 which engages a cam roller 11 mounted on a vertically slideable bar 12 at each side of the machine. The printing heads 5 of the respective printing units are carried on these vertically movable side bars.

Associated with each of the printing units is a holdout latch mechanism comprising a shaft 13 having latch-up hooks 14 at each end thereof. These hooks are adapted to engage under blocks 15 on the reciprocable bars or posts 12 when they are in operative position for preventing the bars from lowering by gravity when the cams 10 are rotated to head lowering position. Associated with the block 15 is a vertical guide strip 16.

So much of the machine as has been described is now in use on standard printing machines of this type.

According to the present invention a lever 17 is secured to the shaft 13 on which the hold-up hooks 14 are carried. The shaft 13 of each printing unit or head is provided with such a lever. Hinged on the lever 17 at 18 is a bell crank lever 19 having a horizontal arm 19^a with a counterweight 19^b at its outer end. The bell crank 19 has a vertically depending arm 19^c. The forward edge of the lever 19 pushes against one face of the lever 17 when the parts are in normal position, as clearly shown in Figure 2, whereby the counterweight 19^b tends to rotate the shaft 13 in a clockwise direction to keep the hold-up hooks 14 in operative position, which is the position shown at the extreme left hand end of the machine in Figure 1. The bifurcated end 20 of a drop link 21 is pivotally secured to the lower end of the arm 19^c at 22. Secured to the link 21 is a spring cam 23. Each printing unit carries a bracket 24 on which is an electro-magnet, preferably a double-pole magnet, 25 located above the link 21. The link 21 is of soft iron as is also the core of the magnet 25 so that neither of these parts will retain residual magnetism upon energization of the magnet windings.

Extending lengthwise of the printing machine under the bed 3 is a reciprocable bar 26 guided at various points in rollers 27 mounted on brackets 28 on the frame of the machine. Secured to the bar 26 in corresponding relation to each printing unit is a cam plate 29. Also secured to the bar 26 in corresponding relation to each printing head and spaced away from the respective cam plates are dogs 30.

Connected to the end of the rod 26 is a

link 31 whose other end is connected to the operating end of a vertical lever 32 mounted on a shaft 33. The lower end of the lever 31 is pivotally connected at 34 to a link 35. The other end of the link 35 is connected with a collar 36 operatively engaging an eccentric 37 on the shaft 8 for the printing unit most nearly adjacent one end of the machine. The eccentric 37 is so disposed on the shaft 8 with reference to the cam 10 that at the proper time the rod 26 will be reciprocated in one direction, and at the proper time will be moved in the opposite direction.

When the rod 26 reciprocates toward the left as viewed in Figure 1, the cam plate 29 for each unit engages the cam 23 on the drop link 21 of each unit and forces the link 21 of each unit up into contact with the poles of the magnet 25. If at this time the magnet 25 for a particular unit is energized, the link 21 will be held in this elevated position. If the magnet is not energized, the link 21 will drop down again just as soon as the rod 26 starts to move toward the right as viewed in Figure 1. If the link 21 is free to drop down, its terminal will fall below the end of the dog 30 as the rod 26 moves toward the right so that no operation of the bell crank 19 will take place and the hold-up hooks 14 of that particular unit will continue to prevent the head from lowering. If, however, the magnet be energized to prevent the link 21 from dropping, then, as the part 26 moves toward the right the forked end 30^a of the dog 30 will engage the terminal of the link 21 and tend to lift the counterweight 19^b. The forked end 30^a has a camming action which will draw the drop link down out of contact with the magnet cores, so that the soft iron of the cores and of the drop links is not injured by one rubbing laterally over the other in tripping the holdout latch. Just as soon as the counterweight 19^b is lifted, the bell crank pressure against the lever 17 is relieved and a pull is exerted by the bell crank on the lever 17, so that the hold-up hooks 14 will swing out of the path of the block 15, thereby allowing the head to descend. Prompt and successful release action is secured by this construction during the brief moment when the weight of the printing head is lifted off the holdout latch.

The magnets 25 are energized at the proper time by means of a novel selector mechanism. This mechanism may be best understood by reference to Figures 3, 4, 5, 6 and 7. This selector mechanism is preferably located at the feeding end of the machine in advance of the first printing head. It is contained in a suitable casing 40. This casing may be provided with conveniently arranged sections which can be removed or opened out to give access to the interior of the casing. In Figure 3 there is shown a hinged cover section at 41 which may be opened on a hinge 42.

The selector is operated from the driving shaft 43 that is geared to the shaft 8 of the first printing head, or otherwise connected with the driving means, so that the selector will move in unison with the operation of the printing machine. On the shaft 43 is a crank disk 44 having a crank pin 45 which operates in a block 46 slidable in the bifurcated end 47 of a beam 48 pivotally mounted on a stationary part of the frame at 49. Pivoted to the free end of the beam 48 at 50 is a second beam 51 which normally rests on the beam 48 and which has a counterweight 52 thereon for causing it to normally lie on the beam 48. Pivoted to the upper beam 51 at 53 is a vertically extending link 54 having a slot 55 in its upper end as best shown in Figure 4. Under ordinary conditions of operation the beam 48 is oscillated in a vertical arc upon rotation of the shaft 43, and this movement is transmitted to the vertical link 54. In the event that the selector mechanism driven through the vertical link 54, as hereinafter described, becomes jammed in any way, the beam 48 can move down independently of the beam 51 on account of the pivotal connection 50.

The selector includes a frame work 56 and supported in this frame work is a transverse shaft 57 having a squared end 58 to which a crank is applied when it is desired to rotate the shaft 57 manually.

Passing through the slot 55 in the upper end of the link 54 is a pin 59 carried on a lever 60 extending out from a sleeve 61 having a working fit on the shaft 57. Adjacent the sleeve 61 is a ratchet wheel 62 which is fixed to the shaft 57, as most clearly shown in Figure 6. The lever 60 carries a pawl 63 that cooperates with the ratchet wheel 62.

Carried on the shaft 57 and secured thereto are spaced-apart sprockets 64. Passing over the sprockets 64 are parallel chains 65. Each of the chains 65 has an even number 45 of links, and they are of the same length. They are held in a substantially L-shaped circuit between upper guide bars 66 and 67 and between lower guide bars 68 and 69. At the end of the guide bars 66-67 and 68-69 most remote from the sprockets 64 is an idler shaft 70 having sprockets 71 thereon over which the chains 65 pass. At the opposite ends of the horizontal guides 66-67 and 68-69 is another idler shaft 72 having sprockets 72^a thereon over which the parallel chains 65 pass. Two spaced-apart disks or wheels 73 on a shaft 74 lie in the bottom of the vertical loop of chain between the sprockets 64 and the sprockets 72^a and serve to keep the vertical loop of chain taut and to keep the chains parallel. The shaft 74 is a floating shaft supported by the loop in the chain and is free to move up and down with any removal or addition of links to the chain. The 65 chains are of a well known type which can

be easily opened to permit the insertion or removal of links so that their lengths can be conveniently varied. At every other joint of the chains the pins ordinarily provided in the chains are replaced by cross rods 75 as best shown in Figures 6 and 7 extending from chain to chain. Each rod serves both as a joint pin for the chains and as a support for a shiftable contact ring or disk carried thereon. This contact ring comprises an insulating sleeve 76 on which is a metal ring or roller 77. The sleeve 76 is freely rotatable on the rod 75 and can slide freely along the rod.

In Figures 3 and 4 the eccentric pin 45 operated by the shaft 43 is in its uppermost position and the vertical link 54 is at the highest limit of its movement. The pin 59 at this time is at the lower end of the slot 55. During the first quarter-revolution of the shaft 43 the vertical link 54 will move down relatively to the lever 60 until the pin 59 on the lever 60 comes into contact with the slot 55. During the remaining half of the downward movement of the crank pin 45 the link 54 acting through the pin 59 will rock the lever 60 downwardly. The pawl 63 will, during this downward movement of the lever 60, rotate the shaft 57 with its sprockets 64 and advance the endless carrier comprising the chains and the rods. The ratchet 62 has one-half as many teeth as the sprockets 64 and the other parts are so proportioned as to move the endless carrier a distance equal to the length of two links, 90 which is equal to the spacing of the rods 75 with their contact rings 77.

During the latter half of the revolution of the shaft 43 the beams 48 and 51 are raised and the link 54 is raised. During the first half of the raising movement of the link 54 the link will move upwardly relative to the pin 59 on the lever 60 until the pin 59 contacts with the lower end of the slot 55. Thereafter the link 54 will raise the lever 60 and the pawl 63 will ride over the teeth of the ratchet wheel 62 without rotating the shaft 57.

The drop of the pawl 63 for engagement with the ratchet 62 upon the next downward movement of the lever 60 is assured by reason of a tail 63^a secured to the pawl. This tail is adapted to contact with a fixed stop element 63^b. As the lever 60 moves up, pivoting about the shaft 57, the tail 63^a swings down into contact with the stop 63^b to cause it to force the pawl down into engagement with a tooth of the ratchet. The roller 78 on the end of the lever 79, which lever is pivoted to the frame at 80, engages in one of the sprockets 64. This roller is pressed into engagement with the teeth of the sprocket by a torsion spring 81. The purpose of the roller 78 is to counteract any frictional resistance in the back motion of the ratchet to thereby hold 120

the shaft 57 with its sprockets 64 against reverse rotation.

Extending across the guides 66 and 69 for the chains are a plurality of strips 82 of bakelite or other insulating material. Ordinarily there is provided one strip 82 for each printing head in the block printing machine. In the selector shown in the accompanying drawings there are 26 of these strips, 10 but this number may be varied according to the number of blocks in the machine to be controlled. Mounted on each strip 82 are a plurality of binding or contact posts 83, the number of binding posts on all of the strips 15 82 being the same. Supported on the under side of intermediate strips 82^a are parallel guide bars 84 as best shown in Figures 5 and 6, these guide bars being of bakelite or other non-conducting material. This forms a plurality of parallel guideways designated *a*, *b*, *c*, *d*, *e*, *f*, *g*, *h* and *i*. There is a binding post 20 83 for each of these grooves or guideways with the exception of groove *a*. None of the plates 82 have binding posts positioned over 25 the channel *a*. Each contact post 83 has a spring contact 85 thereon located in the groove or channel over which the post is located.

Located between the upper series of strips 30 82 and the lower series of strips 82 are longitudinally extending bus bars 86. Secured to and supported on these bus bars are transverse spring contact elements 87 which are preferably of the form shown in Figure 8.

35 Located in advance of the grooves under the upper series of plates 82 is a grooved table 88. The grooved table 88 has a plurality of grooves therein in alignment with the grooves *a* to *i*, inclusive, and is so positioned that the contact rings or rollers 77 on the rods 75 will roll thereover before passing under the cross strips 82. The grooves are V-shaped so that the rollers 77 center themselves with respect to the particular grooves 40 *a* to *i* in which they are to travel.

All of the electromagnets 25 for the several printing heads are connected to one side of a line 90, as shown in Figure 9, leading from any suitable source of current supply, 50 not shown. The bus bars 86 carried across the contact members 87 are connected to the same source of current through a line 91. Leading from the other side of each electromagnet 25 is a wire 93 terminating in a flexible connector which may be attached to any one of the binding posts 83 on the cross strip 82, there being one cross strip for each electro-magnet. The electro-magnets are preferably connected to the respective binding posts 55 83 in consecutive order, the magnet 25 of the first head being connected with one of the binding posts 83 of the first strip 82, the second to the second strip, etc. The carrier travels in the direction of the arrows shown 60 in Figures 3 and 4 so that the first strip 82 is

the upper strip at the right hand end and the last strip is the lower one at the right hand end.

Located at one side of the carrier is a panel 94 to which wires 93, shown in the diagram 70 in Figure 9, lead. Each wire 93 passes through an opening in the panel 94 and has a flexible end portion 93^a having a cap 95 adapted to be snapped onto or otherwise secured to the contact posts 83. Where necessary the flexible connector 93^a may be split so that certain desired printing heads may be selectively connected to two or more contact posts 83 on the same strip. On the panel 94 there is an idle post 96 for each row of contact 75 posts 83 so that if a given head is not to be operated the connector 95 for controlling this electro-magnet may be hooked out of the way on this idle post.

As hereinbefore pointed out, in the usual block printing machines the printing blocks are 18 inches wide. It is therefore convenient to imagine the material being printed upon as being composed of successive 18-inch sections. Assume that definite lengths of 80 material are being printed upon, say strips 121 feet long, and that this is being printed into rugs of 12-foot lengths. Each rug is therefore composed of eight 18-inch sections. However, in the printing of rugs having a 85 cross border at each end thereof, the printing blocks for the cross borders are so designed that they will print the cross border at the end of one rug and the cross border at the beginning of the next rug at the same time. In other words, the strip is cut after the printing into rug lengths, and the line of the cut is through the center of the border pattern. Therefore the printed rug is composed of 90 seven complete 18-inch sections and two half-sections of 9 inches each. This is clearly shown in Figure 11 where space *x*—*x* indicates the ends of adjacent rugs. The rugs will be cut on the line *y*—*y*, so that at the end of each rug there is a 9-inch section *x*—*y*. 100 The field of the rug is composed of similar sections *z*—*z*, there being seven of these sections in all. Of course it will be understood that the sections are not actually visible in the finished product but that they are, nevertheless, printed in sections.

115 For the purpose of the present invention it may be assumed that the rug is printed in only three colors, with the simple pattern shown in Figure 11. Six printing heads would be necessary to reproduce this pattern. The first head would print the designs *l* and *l'* in the section *x*—*x*, the second head would print in the field in the border section *x*—*x*. 120 The next head will print the part *l*². The next head will print in the design *l*³ in another color. The next head will print the field color in the section having designs *l*² and *l*³, and the last head will print in the plain 125 130

field sections of the rug, which sections are designated *m*.

In the printing of this pattern the head which prints the designs *l* and *l'* would only make a single impression on the rug and then raise. It would not be lowered again under ordinary circumstances until seven sections of the rug had passed beneath it after which it would again lower and then raise and remain up for seven more sections. This would be true also of the head which prints the field color around the border patterns *l* and *l'*. The same sequence would follow in the printing of the patterns *l²* and *l³* and in the printing of the field color in the section containing the pattern *l²* and *l³*. However, the block which prints the sections *m* would lower six times in succession and then be held up for two sections and then print again six times in succession, there being ordinarily always six of the sections *m*.

The material being printed upon is delivered to the machine from a roll. According to some methods, the material, after being printed upon, is festooned vertically in a drying stove. According to another practice, the material, after being printed upon, is cut into definite lengths and dried on racks in horizontal ovens. For instance, such horizontal ovens may conveniently receive strips 120 feet in length. Consequently, with this latter practice, the material is printed to give an even number of rugs in each 118½ feet and leave an 18-inch strip on each 120 foot length; for example, nine 12-foot rugs and one 10½-foot rug. When the 120 foot mark comes along, the border block prints twice in succession. The reason for this is that each border block prints borders facing in opposite directions, one finishing off the one rug and one starting the next. When the block printing the double border drops twice in succession, there is a small printed section 18 inches long containing two borders facing each other. The strip of material is cut at the end of the last complete rug in the strip and the 18-inch strip with the two borders facing each other provides for the attaching of a clamp to the next length of goods to pull it into the oven. The dropping of the border block twice, besides forming the 18-inch clamping strip, initiates the beginning of the next complete rug.

Since the material is advanced in 18-inch sections through the machine, the selector preferably has a rod 75 and contact 77 for each 18-inch section in the 120-foot length, that is, eighty such rods and contacts.

To print the pattern shown in Figure 11 the first contact roller 77 may be set to travel along one of the grooves, say groove *b*, in the selector. This roller will control the first 18-inch section of the strip to be printed upon. The next roller to control the printing on the next 18-inch section in which ap-

pear the patterns *l²* and *l³* will be positioned to travel along the groove *c*. The next roller corresponding to the next 18-inch section will be set to travel along the groove *d*. Since the succeeding five sections have the same pattern as the third section, these succeeding five rollers will also be set to travel along the groove *d*. The next 18-inch section will be a border section so that the roller for this section will be set to follow the first roller in the groove *b*. The next roller in turn will be set to travel in the groove *c* and the succeeding six rollers set to travel in the groove *d*. This sequence of arrangement will follow throughout the length of the chain.

Assume that the first head prints the patterns *l* and *l'* of the border section. Assume that the second head prints the field in the border section. Then the connector 93^a for the first printing head will connect to that contact post 83 on the first cross strip 82 which is over the groove *b*. The connector 93^a for the next head is connected to the corresponding contact post on the second series. If the third head prints the portion *l²* the contactor 93^a for the third head will be connected to a connector 83 in the third row positioned over the groove *c*. If the fourth head prints the pattern *l³*, then the connector 93^a for the fourth head is connected to the contact post of the fourth series over groove *c*. If the fifth head prints in the field around the designs *l²* and *l³* the connector for the fifth head is connected to the post of the fifth series over the groove *c*. The sixth head will print the sections *m* and the connector for the sixth head will be connected to that connector post of the sixth row which is over the section *d*. All of the other printing heads will be idle.

In the progress of printing, as the first roller moves under the first contact in the groove *b* the magnet 25 is energized to cause the descent of the printing head 5 controlled thereby. When the first roller is moved under the second contact in the groove *b* the second printing head 5 is operated. The remaining contacts in the first groove *b* are not connected in any live circuit, so that the first roller will not operate any more printing heads, and printing heads 1 and 2 will not operate until the ninth roller engages the first contact in groove *b*. Likewise, the other rollers traveling in the proper grooves will energize the various magnets at the proper time to give the desired sequence of printing. Each 18-inch section will only be printed on when the roller representing the section completes a circuit through the magnets 25.

Should an imperfection in the material be seen, the order of printing can be changed so that a defective rug need not be printed. The material lies flat on the bed of the machine for some distance in advance of the first printing head so that it can be inspected before it

reaches the first printing head. Likewise, the selector disks or rollers do not come into operative position until the particular section controlled by a particular roller is about to be printed on. For instance, in Figure 11, it may be assumed that the material between $r-r$ is defective. This may be but a small defect, or it may be a defect which covers one or two or possibly more 18-inch sections. If the defect is contained within but a single section the roller for that particular section is drawn into the groove which prints the cross border. The roller for the section immediately following is also set in the groove which controls the printing of the cross border. Thus the cross border pattern is printed twice in succession and the defective material between the lines $r-r$ is cut out. It will be seen that one rug is finished off just before the defect and the printing of the next rug follows just after the defect has passed and that the only material which is wasted is that between the lines $r-r$.

If the defective material is of a length greater than one section, the first roller for the defective section is set to cause the printing of the cross border while the succeeding rollers are moved to the extreme right as viewed in Figure 7 so that rollers for the defective sections travel along the groove a in which there are no contacts at all. Succeeding rollers are set to travel in the groove a until all of the defective material has been skipped, after which the contact rollers are set to resume the regular sequence of printing.

The material which is cut into strips to be printed is generally of such length that a definite number of rugs of a certain size can be printed from a given piece. If one or more sections is defective, an even number of rugs can not be printed on the piece. With the present invention, a complete rug of shorter length can be printed on the odd length at the end of the strip. If, for instance, 12-foot rugs which are eight 18-inch sections in length are being printed, and the odd piece at the end will allow for printing six 18-inch sections, the sequence of printing can be changed. A complete rug of shorter length is produced, and it is done by so setting the rollers that fewer field sections will be printed than are ordinarily required in the 12-foot rug.

The invention therefore effects a considerable saving of material and a considerable saving of paint. It is highly flexible because of the provision of a separately adjustable selector contact for controlling each individual section in the length of the strip being printed upon.

The setting of the contacts in regular sequence can be easily done by an attendant, and the order of sequence quickly changed without stopping the machine when the

necessity for doing so becomes apparent. By putting a crank on the squared end 58 of the shaft 57, the contact carrier, that is the chains, can be operated manually so as to initially set all of the contact rollers or disks in the proper position to carry out the printing of the strip. In the printing of rugs the contact disks or rollers are always set so as to begin with the printing of a border pattern and end off the piece with the printing of a border pattern. In view of the fact that a large number of rugs of the same pattern are run off at one time, the selector disks do not have to be reset for the printing of each strip. Resetting is necessary, however, after a variation is required because of some defect being encountered.

It will be seen that the contact carrier is intermittently advanced at a rate corresponding exactly to the rate of movement of the material through the printing machine. The extent of movement of the carrier may of course be less than the actual movement of the goods, but the same corresponding relation is maintained at all times.

In Figure 10 there is illustrated diagrammatically the sequence in the movement of the printing heads. In this figure the material is represented by the numeral 100 and the pattern is of geometrical form. The pattern on each section is generally the same, being comprised of a series of squares 101. The printing blocks are designated 102 to 108, inclusive. The first printing block 102 prints the field pattern in every section leaving the blank squares 101. The printing block 103 prints a colored pattern in the squares of alternate sections. The printing block 104 prints another color in the same sections that are printed by the block 103. Likewise, block 105 prints in the same sections as the blocks 104 and 103 but still another color. The blocks 106, 107 and 108 print different colors in different patterns in the alternate sections between those printed by the blocks 103, 104 and 105. Since the material is moved intermittently through the machine the length of one section at a time and since the difference between the centers of the blocks is equal to twice the length of a section, it is apparent that a given section is first alternately located under a block and then between blocks. The printing block 102 must print on every section.

The blocks 103, 104 and 105 print on alternate sections and the blocks 106, 107 and 108 print on the intervening sections. Blocks 102, 103, 104 and 105 all come down into printing position in unison while the blocks 106, 107 and 108 are latched up. After blocks 102, 103, 104 and 105 are printed and are raised and the material is advanced the length of one section the blocks 102, 106, 107 and 108 are lowered while blocks 103, 104 and 105 are latched up.

With an arrangement of this kind the

connector 93^a for the first printing head would be split and coupled to two posts 83 on plate 82 for grooves *b* and *c*. The posts for groove *b* on the second, third and fourth plates would be connected to the magnets for the second, third and fourth heads. The posts for the groove *c* would be connected to the magnets which control printing blocks 106, 107 and 108. The rollers would be alternated first to travel through groove *b* and next to travel through groove *c*. By reason of the split connection for the first head rollers going through grooves *b* and *c* would both operate head 102. Rollers going through groove *b* would also operate heads 103, 104 and 105. The rollers going through groove *c* would operate blocks 106, 107 and 108. Since the rollers are progressively alternated, the operation of the heads 103, 104 and 105 would be alternated with the operation of the heads 106, 107 and 108.

The master controller for setting the selector disks in the proper predetermined relation is located at the right hand end of the selector mechanism as viewed in Figure 3. Secured to the ratchet 62 on the shaft 57 (as best shown in Figure 6) is a sprocket wheel 110. Supported in the frame work is a pin 111 upon which is carried a built-up frame 112, (see Figures 12, 19 and 20) held in spaced relation by cross bolts. Located between the lower end of the bars 112 and having a working fit on the pin 111 is a sprocket 113. The sprocket 113 is driven from the sprocket 110 by a chain 114. Mounted in bearings at the top of the side pieces 112 that form the boom is a sleeve 115 having a sprocket wheel 116 thereon and the sleeve 115 is rotated by means of a chain 117 passing over the sprocket 116 and passing around a second sprocket 118 connected with the sprocket 113. Received within the sleeve 115 is one end of a removable spindle 119 (Figs. 23 and 24). The spindle 119 is yieldably driven by means of a U-shaped spring key 120, shown in detail in Figure 21. The parallel arms of this spring U-shaped key 120 are received in slots cut in the sleeve 115, and bear against flattened sides of the spindle 119 as shown in Figure 21. Ordinarily, rotation of the sleeve 115 will be transmitted to the spindle 119 and the two will be held against relative movement. However, the spindle 119 can be rotated in either direction with reference to the sleeve 115 merely by gripping the spindle and turning it as desired independently of the sleeve. When this is done the parallel arms of the U-shaped key 120 will spread. A resilient driving connection of a simple type is thus provided by the U-shaped key spring 120.

At the upper end of the boom 112 is a specially formed member 121 having a wing 122 thereon. This wing or flange 122 is pro-

vided with a notch 123 (see Figure 19), for the purpose hereinafter described.

Supported in the upper part of the frame of the machine at the right hand end as viewed in Figures 3, 4, and 5, is a transversely extending bar 124 (see Figure 14). Slidable on the bar are two blocks, 125 and 126. The blocks are so located that their opposed faces may be brought into contact with the sides of the selector disks 77 as they successively move opposite the bar 124, as best shown in Figure 5. With reference to Figure 5 it will be seen that the disk 77 is resting between opposed faces of the blocks 125 and 126.

Mounted on the frame of the machine are two bell crank levers 127 and 128, the pivot points of which are located at 129 and 130, respectively. The upper end of the vertical arm of the crank 127 is provided with a rounded head 127^a which is received in a slot in the sliding block 125. Similarly, the upper end of the vertical arm of the bell crank lever 128 has a rounded head 128^a received in a slot in the sliding block 126. A tension spring 131 is connected to the horizontal arm of the bell crank lever 127 (see Figure 12). A tension spring 132 is connected to the horizontal arm of the lever 128. As viewed in Figures 12 and 14, lever 127 is always urged by the spring 131 toward the right and the lever 128 is always urged by its spring 132 toward the left. Any oscillatory movement of the levers 127 and 128 serves to slide blocks 125 and 126 on the bar 124.

For operating the levers 127 and 128 against the action of the respective springs 131 and 132 there is provided a vertically reciprocable bar 133. (See Figures 12 and 13.) Projecting from the side of the beam 48 (see Figures 3 and 12), is a pin 134 on which is a sleeve 135 having transverse trunions 136 thereon to which the bifurcated end 133^a of the rod 133 connect. There is, therefore, a substantially universal connection between pin 134 and the vertically reciprocable rod 133. The up-and-down movement of the beam 48 serves to impart an up-and-down movement to the bar 133. At the upper end of the bar 133 is a substantially T-shaped head 137 having inclined portions 138 and parallel side portions 139. Upon downward movement of the rod 133, as viewed in Figure 12, the inclined surfaces 138 engage rollers 140 on the levers 127 and 128 to open the levers, spreading them apart against the action of their respective springs 131 and 132. By this spreading movement of the levers 127 and 128 the block 125 is moved to the extreme left hand end of the bar 124 as viewed in Figure 14 and the block 126 is moved to the extreme right hand end of the bar 124. As long as the rod 133 is held down the blocks 125 and 126 are held at the extreme limits of their movement. When the

block 125 is moved to the extreme left hand end of the bar 124 as viewed in Figure 14 and the block 126 is moved to the extreme right hand end of the bar 124. As long as the rod 133 is held down the blocks 125 and 126 are held at the extreme limits of their movement. When the

rod 133 lifts, the levers 127 and 128 are free to move under the action of their respective springs 131 and 132 to a predetermined position as determined by the control mechanism 5 as hereinafter more fully explained.

The overhanging end of the spindle 119, as best shown in Figures 4, 5 and 12, is provided with spaced apart sprockets 141 over which is hung an endless carrier 142 comprised of spaced-apart roller chains 143 connected by rods 144 at every other joint, the construction of the endless belt 142 being generally similar to the construction of the endless carrier in the selector. Adjustably set 10 to the rods 144 are disks 145. These disks may be adjusted along the rods 144 and secured in a given position by set screws 146 (see Figure 5). The width of the control belt assembly 142 is substantially the 15 same as the width of the selector carrier, and the belt 142 is in alignment with the selector. The disks 145 are set on their rods 144 in a predetermined relation, so that each one of the disks 145 is opposite one of the grooves 20 *a* to *i*, inclusive.

In its normal operating position the belt 142 is so located that the disks 145 will progressively move into the path of travel of the blocks 125 and 126 on the bar 124. This 25 is best shown in Figure 5 wherein it will be seen that one of the disks 145 is located between the blocks 125 and 126.

The belt 142 is preferably of a length which will provide for a number of disks 145 equal 30 to the number of sections in the rug to be printed. Belts of different lengths can be kept in stock and easily interchanged when desired. The disks 145 are set opposite grooves *a* to *i* in the sequence in which the selector 35 rollers 77 are to be placed. For instance, if the first roller starting at a given point is to go in groove *b* the first disk 145 is set in line with groove *b*. If the next succeeding three rollers 77 are to travel along groove 40 *c* the next succeeding three disks 145 are set opposite groove *c*. If there are eight sections in the rug to be printed, there will be eight of the disks 145 in the chain 142, and each one will be set, in this manner, 45 opposite one of the grooves *a* to *i*.

In the operation of this mechanism, the rod 133 moves down, spreading the blocks 125 and 126 to the extreme limits of their 50 movement. The blocks 125 and 126 are spread apart on the initial downward movement of the bar 133, as the bar 133 is moved down by the movement of the beam 48. The downward movement of the beam 48 also 55 advances the selector carrier through the selector mechanism, as hereinbefore described, but the carrier in the selector does not move except in the last half of the downward movement of the beam due to the lost motion provided by the slot 55 in the oper- 60

ating link 54. The blocks 125 and 126 are therefore spread to their full limit before the selector carrier is advanced. The control chain 142 is advanced one step at the same time the selector is advanced through the 65 sprocket chains 114 and 117.

When the beam 48 completes its upward movement, the T-shaped cam 137 is not effective for keeping the levers 127 and 128 spread apart, and springs 131 and 132 urge their 70 respective levers toward each other. As the levers move toward each other, sliding the blocks 125 and 126 toward each other, the selector disk 77 which is then in the path of travel of either of the blocks 125 and 126 will 75 be slid along its supporting bar 75 toward the other block. The sliding movement of the blocks 125 and 126 is limited by reason of the opposite faces of the two blocks coming into contact with one of the fixed disks 80 145 of the control chain 142. The selector disk 77 is thus brought to a central position between the two blocks 125 and 126. In this central position it is opposite one of the grooves *a* to *i* because of the disk 145 being 85 opposite that groove. By reason of the fact that the levers 127 and 128 are moved toward each other by means of springs the extent of movement of either lever is variable. For instance, if a given contact disk is supposed 90 to move along groove *a*, the block 126 would not be slid along the bar 124 at all while block 125 would slide to the greatest possible extent along the bar 124. If the selector disk 77 were to be moved into the other extreme 95 groove *i*, block 125 would not move at all and block 126 would move the full distance. For moving the selector 77 into any of the grooves intermediate *a* and *i* both blocks 125 and 126 move but the distance which they move is only equal when the selector disk is to be 100 entered in the central groove.

As the machine continues to operate each selector disk 77 will automatically be moved to the desired position by the blocks 125 and 126. The sequence in the setting of the selector disks 77 will be repeated with every 105 complete circuit of the chain 142.

If a defect in the material being printed upon is encountered, the entire master controller must be rendered inoperative to destroy the regular sequence of printing as hereinbefore explained. For this purpose, there is provided in the upper part of the frame work a cross shaft 150 with a vertically extending operating handle 151. This construction is most clearly shown in Figures 14 and 15. Projecting laterally from the shaft 150 is an arm 152. Under normal operating conditions the handle 151 is in a vertical position and the end of the arm 152 engages in the notch 123 of the specially formed piece 121 on the upper end of the boom 112. This serves to hold the boom over toward the left as viewed in Figure 4. When the boom 115 120 125 130

is held over to the left in this way the control chain 142 is in a position where the stop disks 145 will be engaged successively upon movement of the chain by the blocks 125 and 126. By rocking the hand lever 151 to the right as viewed in Figure 4 the arm 152 is raised out of contact with the notch 123 allowing the upper end of the boom 112 to swing to the right a distance sufficient to 10 keep the stop disks 145 out of the path of movement of the blocks 125 and 126.

Above the shaft 150 and above the slide bar 124 is an inverted channel 153. Pivoted at one end of the channel is a hold-out dog 154 and pivoted at the other end of the channel is a hold-out dog 155. This construction is clearly shown in Figure 14. The end portion 154^a of the dog 154 is received in a slot 156 in a counterweight 157. 15 The counterweight normally holds the dog 154 in inoperative position. Likewise, the end portion 155^a of the dog 155 is entered in a slot 156^a of a counterweight 157^a. The counterweight 157^a normally holds the dog 20 155 out of operative position. On the shaft 150 under the counterweight 157 is a collar 158 having two cut out surfaces 159 and 160 (see Figure 16). On the other end of the shaft 150 is a collar 161 having a single 25 flat surface 162. When the handle 151 is in the vertical position shown in Figure 4 the flat surface 159 of the collar 158 is under the counterweight 157 and the flat surface 162 of the collar 161 is under the counterweight 157^a. Upon rocking the handle 151 to the right against a stop 151^a, as viewed in Figure 4, the collar 161 is rotated. As the flat surface of the collar rotates from under the counterweight 157^a, the counterweight 157^a is raised allowing the hold-out latch or dog 155 to drop. On the other hand, the flat surface 160 on the collar 158 allows the counterweight 157 to remain in normal position and the latch 154 can be held up. 30

When the handle 151 is rocked to the right against the stop 151^a, allowing the boom 112 to fall back, the latch 155 drops, and the block 126 is held from movement toward the left. The block 125, however, is free to slide 35 and as the machine continues to operate the block 125 will slide each successive contact ring 77 over to the extreme right as viewed in Figure 5. When the contact disks 77 are moved to the extreme right, they travel along the groove *a* in which there are no contacts.

When the handle 151 is rocked to the left against a stop 151^b, permitting boom 112 to fall back, the block 126 is held from movement toward the left (Fig. 14) and the block 40 125 is held from movement to the right, permitting rings 77 on the shafts 57 to enter the grooves as previously set up.

Thus when defective material is encountered the handle 151 is swung to the right 45 throwing the control chain 142 out of opera-

tive position and causing the block 125 to move each succeeding disk into the idle groove *a*. When the sequence of printing is resumed the operator advances or retarded the chain 142, as the case may be, and then swings the lever 151 back to its normal operating position. The chain 142 can be easily advanced or retarded by means of the slip key provided in the U-shaped spring 120 for connecting the spindle 119 with the sleeve 115. 75 Likewise, if a piece of odd length is encountered so that a fewer number of sections has to be printed the operator can advance the control chain 142.

From the foregoing it is believed that the 80 construction and the operation of my invention may be readily understood.

The length of the chains 65 of the selector are adjusted to correspond, in proportion, to the length of the strips to be printed. The 85 connectors 93^a for the various printing heads are selectively engaged with the proper contact post 83. This setting does not have to be changed as long as the same rug design is being printed. A control chain 142 is placed 90 on the sprockets 141 on the spindle 119, the length of the control chain corresponding to the number of sections in the pattern to be printed. The adjustable disks 145 are set to a predetermined position to produce the desired 95 pattern before the carrier 142 is placed on the spindle. The shaft 57 is turned by applying a crank to the squared end 58 until all of the selector disks 77 which are in the machine 100 at the time of starting are traveling along the groove *a*. When the selectors 77 have been set in this way the handle 151 is rocked to bring the carrier 142 into operative position and the carrier 142 is set to the proper 105 starting place. The machine is then started, and as the material is moved intermittently into and through the machine the chains 65 are correspondingly advanced. As the 110 chains 65 advance the successive disks 77 are set to the proper position by the slide blocks 115 125 and 126. This movement of the blocks 125 and 126 is controlled by the setting of the stops 145 on the carrier 142. The printing will then automatically take care of itself. When a defect in the material is observed, the operator temporarily throws the 115 control chain 142 into inoperative position by movement of the lever 151 and at the same time renders the contact shifting block 126 inoperative so that successive contact disks 77 are jumped to the inoperative groove *a*. When the defect is passed the control chain 142 is advanced or retarded, the lever 151 120 swung back to its normal position, and the proper sequence of printing will be resumed and continued thereafter. If an uneven 125 length of material is encountered so that the usual length of rug being printed into the piece can not be made, the control chain 142 can be advanced to cause the printing of one 130

or more field sections to be omitted. When this is done only a single rug of odd length will be printed and then the printing of rugs of normal length will be automatically resumed.

In the printing of piece goods all of the heads operate in unison unless special odd patterns are being printed into the piece. For this purpose there is provided a switch 10 S, see Figures 3 and 9, which, when closed energizes all of the magnets without regard to the selector.

It will therefore be seen that the control mechanism is one which is very flexible and extremely simple in its operation. It allows the sequence of printing to be varied at any time and introduces a new method into the printing of floor coverings. It permits of the printing of rugs of different lengths. It 20 allows the machine to print on each side of a defective section without printing on the defective goods.

The hold-out mechanism described in connection with the present invention is one 25 wherein the magnets serve only to hold up the drop links 21 while the actual operation of the hold-out mechanism is effected by the power-actuated rod 26. This requires the use of only comparatively small currents in 30 the magnets 25. Arcing and burning out of contacts is thus avoided and the life of the selector mechanism increased.

While the invention finds its greatest utility in the printing of rugs it will also be 35 understood that the machine can be employed equally well in the printing of piece goods.

The invention has also been specifically described in connection with the printing of strips of material of definite length wherein 40 the chains 65 provided a contact roller 77 for each individual section in the length of the strip. However, the machine may also be well adapted to the printing of very long strips of material or for continuous printing.

The invention has also been specifically 45 described in connection with machines of standard type wherein the section printed upon is an 18-inch section. It will be understood that this is merely illustrative and 50 shows the manner in which the present invention is applicable to standard practice.

While I have described a master controller for use in combination with the selector mechanism, it will be understood that the 55 selector disks 77 can be conveniently adjusted by hand without the provision of the master controller and that the invention is not restricted to the use of this master controller.

The particular construction shown in the 60 drawings and herein described is merely 65 illustrative of a preferred embodiment of the invention and it will be understood that various changes and modifications may be made 70 within the contemplation of my invention

and under the scope of the appended claims.

I claim:

1. In a block printing machine through which material to be printed is intermittently advanced in sections and having a plurality of printing heads to be controlled, a normally operative latch mechanism for holding each of such heads inoperative, a common releasing mechanism for operating the several latches, an electromagnet for each such head for selectively causing the releasing mechanism to release the latches controlling the operation of the several heads, and a selector for controlling the magnets adjustable to selectively prevent the printing on any one or more sections in the material in the machine.

2. In a block printing machine having a plurality of printing heads to be controlled and adapted for printing sections of the area of material which is intermittently advanced through the machine, an electric control element for each head to be controlled, a row of contacts for each electric control, the respective rows being progressively disposed, means for selectively connecting the electric control element for each head to be controlled with any one of the contacts in its row, a carrier movable progressively past the several rows of contacts, and a succession of independently adjustable contacts on said carrier, each of which is arranged to successively cooperate with correspondingly positioned contacts in the several rows.

3. A trip control for block printing machines having a plurality of printing heads to be controlled comprising an electro-magnet for controlling the movement of each head to be controlled, a transverse series of contacts for each electro-magnet, means for selectively connecting each electro-magnet with at least one contact in its transverse series, a carrier progressively movable past the transverse series of contacts, said carrier having a succession of contact elements thereon which are shiftable transversely of the movement of the carrier, whereby each element may be selectively positioned to travel past corresponding contacts in the several transverse series.

4. A trip control for block printing machines having a plurality of printing heads to be controlled including an electro-magnet for each printing head to be controlled, a movable endless carrier having a succession of transversely shiftable contact elements thereon, a plurality of guide ways disposed side by side through any one of which a given contact element on said carrier may be selectively positioned to travel, succeeding transverse rows of contacts in the guide ways, which contacts are adapted to be engaged by said contact elements moving along the guide ways, and means for selectively connecting a given electro-magnet with any one of the

contacts in a given transverse row, there being a transverse row of contacts for each electro-magnet, and means for moving the carrier.

5. A trip control for block printing machines having a plurality of printing heads to be controlled comprising an electro-magnetic means for controlling the movement of each head to be controlled, a row of contact elements for each head to be controlled, means for selectively connecting the electro-magnetic means for each head to be controlled with one of the contact elements in its corresponding row, a succession of transversely shiftable contact members adapted to cooperate with said contact elements, and means for effecting relative longitudinal movement between the transversely shiftable elements and the successive rows of contacts, whereby each of said transversely shiftable elements is progressively engaged with one contact in each transverse row.

6. The combination with a block printing machine through which material to be printed upon is intermittently advanced, of a selector for controlling the movement of the printing blocks and including an endless carrier having an independent circuit controlling element movable transversely thereof for each section of material in the printing machine, and transverse rows of contacts cooperatively disposed with respect to the carrier.

7. In a block printing machine through which material is intermittently advanced in sections and having a plurality of printing heads to be controlled, an electro-magnet for controlling the operation of each head to be controlled, and a selector for controlling the magnets adjustable to selectively prevent the printing on any one or more sections in the material in the machine, said selector including an endless carrier having a succession of independently adjustable contacts thereon, a frame in which the carrier moves having a series of parallel guideways therein, one of said guideways always being an idle one, and contacts in the other guideways, there being a contact in each of said guideways except the idle one for each head to be controlled, and means for selectively connecting the control of any head with a contact in any of said guideways, the adjustable contacts of the carrier being adapted to be positioned to travel in any one of said guideways and cooperate with the contacts therein.

8. The combination with a block printing machine through which material to be printed upon is intermittently advanced in sections and having a plurality of printing heads to be controlled with an electric control for each head to be controlled, of a selector having a movable carrier with a succession of independently adjustable contacts thereon, said selector having a successive series of fixed

contacts thereon, one of such series being provided for each printing head to be controlled, and means for selectively connecting the electro-magnetic control for each head to be controlled with any one of the contacts in its corresponding series, the contacts on said carrier being adapted to cooperate with the contacts in the several fixed series, and means for moving the carrier.

9. In a block printing machine through which a strip of material is intermittently moved in sections, a plurality of printing heads to be controlled, an electric control unit for each head to be controlled, and a selector for the electric control units containing a succession of contact elements adapted to travel along any one of several paths of travel, said contacts being shiftable from one path to another at one point of their travel, successive fixed contacts in some of said paths of travel for cooperation with said succession of contact elements, and means for progressively advancing the succession of contact elements.

10. In a block printing machine through which material is intermittently advanced in sections and having a plurality of printing heads to be controlled, an electro-magnet for controlling the operation of each head to be controlled, and a selector for controlling the magnets adjustable to selectively prevent the printing on one or more sections of material in the machine, said selector comprising a carrier having a plurality of transverse rods thereon, the number of rods exceeding the number of sections of material which the machine will accommodate, a slidable contact element on each rod, a frame in which the carrier is movable, a transverse row of contacts on said frame for each printing head to be controlled, means for selectively connecting the electro-magnet of each head to be controlled with any one of the contacts in its corresponding series, the adjustable contact members on said rods being adapted to cooperate with the contacts in the several transverse series for controlling the energization of the respective electro-magnets.

11. In a block printing machine through which a strip of material is intermittently moved in sections, a plurality of printing heads to be controlled, an electric control unit for each head to be controlled and a selector for the electric control units comprising a carrier having a succession of transversely adjustable contact elements thereon adapted to travel along any one of several paths of travel upon movement of the carrier, said contacts being shiftable from one path to another at one point in the travel of the carrier, successive fixed contacts in some of said paths of travel for cooperation with the contact elements on the carrier, means for selectively connecting the electric control units of the respective heads with said fixed contacts, means for intermittently moving the carrier,

a master controller for arranging transversely shiftable contact elements on the carrier in a predetermined manner, said master controller including a second carrier having a succession of transversely adjustable stop members thereon, and means for moving said second carrier in synchronism with the first.

12. In a block printing machine through which a strip of material is intermittently moved in sections, a plurality of printing heads to be controlled, an electric control unit for each head to be controlled, and a selector for the electric control units comprising a carrier having a succession of transversely adjustable contact elements thereon adapted to travel along any one of several paths of travel upon movement of the carrier, said contacts being shiftable from one path to another at one point in the travel of the carrier, successive fixed contacts in some of said paths of travel for cooperation with the contact elements on the carrier, means for selectively connecting the electric control units of the respective heads with said fixed contacts, means for intermittently moving the carrier, a master controller for arranging transversely shiftable contact elements on the carrier in a predetermined manner, said master controller including a second carrier having a succession of transversely adjustable stop members thereon, a spindle upon which the second carrier is mounted, a sleeve in which the spindle is received, a spring key for yieldably connecting the spindle and the sleeve, means for operatively connecting the sleeve with the said first carrier, and means for driving the first carrier.

13. The combination with a block printing machine having a driving mechanism, of a selector having a carrier on which are a plurality of independently adjustable contact elements, the number of contact elements exceeding the number of printing heads to be controlled, said selector also having several series of fixed contacts, one series for each head to be controlled with which the contact elements of the carrier are adapted to cooperate, and means for intermittently moving the carrier in synchronism and proportionately to the movement of material through the printing machine.

14. A block printing machine as defined in claim 2 characterized by the provision of a master controller for successively adjusting the independently adjustable contacts of said carrier.

15. A block printing machine as defined in claim 2 characterized by the provision of a master controller for successively adjusting the independently adjustable contacts of said carrier, said master controller being movable into and out of operative position.

16. A block printing machine as defined in claim 2 characterized by the provision of a master controller for successively adjusting

the independently adjustable contacts of said carrier, said carrier and said master controller being connected together, and means connected with the printing machine for operating them.

17. A trip control for block printing machines as recited in claim 3 characterized by the provision of a master controller for successively moving the shiftable contact elements of the carrier to the desired position in a predetermined sequence, said master controller comprising an endless carrier having stop elements thereon, shifting blocks for cooperation with the stop elements, said shifting blocks being in the path of travel of the shiftable contact elements of the carrier, and means for imparting reciprocating movement to the shifting blocks, said carrier and said master controller being connected for operation in unison.

18. In a block printing machine having a plurality of printing heads to be controlled beneath which a strip of material is intermittently advanced in uniform sections and having a plurality of printing heads with an electric control for each head to be controlled, a selector comprising a movable carrier having a series of transversely shiftable contacts thereon, the number of shiftable contacts exceeding the number of sections of material which are received in the machine at one time, a plurality of parallel guide ways for the contacts, a contact post in each guide way for each printing head in the machine, means for selectively connecting the electric control of each head to be controlled with one of the contact posts in any one of the several guide ways, and means for intermittently moving the carrier in synchronism with the operation of the printing machine.

19. In a block printing machine having a plurality of printing heads to be controlled beneath which a strip of material is intermittently advanced in sections and having a plurality of printing heads with an electric control for each head to be controlled, a selector comprising a movable carrier having a series of transversely shiftable contacts thereon, the number of shiftable contacts exceeding the number of heads to be controlled, a plurality of parallel guide ways for the contacts, a contact post in each guide way for each printing head to be controlled, means for selectively connecting the electric control of each head to be controlled with one of the contact posts in any one of the several guide ways, means for intermittently moving the carrier in synchronism with the operation of the printing machine, and a master controller for moving the shiftable contacts into line with various guide ways in accordance with a predetermined sequence.

20. In a block printing machine having a plurality of printing heads to be controlled beneath which a strip of material is intermit-

tently advanced in sections and having a plurality of printing heads with an electric control for each head to be controlled, a selector comprising a movable carrier having a series of transversely shiftable contacts thereon, the number of shiftable contacts exceeding the number of heads to be controlled, a plurality of parallel guide ways for the contacts, a contact post in each guide way for each printing head to be controlled, means for selectively connecting the electric control of each head to be controlled with one of the contact posts in any one of the several guide ways, means for intermittently moving the carrier in synchronism with the operation of the printing machine, and a master controller for moving the shiftable contacts into line with various guide ways in accordance with a predetermined sequence, said master controller being movable into and out of operative position.

21. In a block printing machine having a plurality of printing heads to be controlled beneath which a strip of material is intermittently advanced in sections and having a plurality of printing heads with an electric control for each head to be controlled, a selector comprising a movable carrier having a series of transversely shiftable contacts thereon, the number of shiftable contacts exceeding the number of heads to be controlled, a plurality of parallel guide ways for the contacts, a contact post in each guide way for each printing head to be controlled, means for selectively connecting the electric control of each head to be controlled with one of the contact posts in any one of the several guide ways, means for intermittently moving the carrier in synchronism with the operation of the printing machine, a master controller for moving the shiftable contacts into line with various guide ways in accordance with a predetermined sequence, and means for rendering said master controller inoperative.

22. In a block printing machine having a plurality of printing heads to be controlled beneath which a strip of material is intermittently advanced in sections and having a plurality of printing heads with an electric control for each head to be controlled, a selector comprising a movable carrier having a series of transversely shiftable contacts thereon, the number of shiftable contacts exceeding the number of heads to be controlled, a plurality of parallel guide ways for the contacts, a contact post in each guide way for each printing head to be controlled, means for selectively connecting the electric control of each head to be controlled with one of the contact posts in any one of the several guide ways, means for intermittently moving the carrier in synchronism with the operation of the printing machine, a master controller for moving the shiftable contacts into line with various guide ways in accordance with a predetermined se-

quence, and means for driving the master controller synchronously with the carrier.

23. In a block printing machine having a plurality of printing heads to be controlled beneath which a strip of material is intermittently advanced in sections, an independent electric control for each printing head to be controlled, a selector comprising an endless chain having a succession of parallel rods thereon, a transversely shiftable contact member on each rod, parallel guide ways adjacent the path of travel of the chain along which the contact elements are adapted to travel, a succession of contacts in each groove corresponding in number to the number of printing heads to be controlled, means for selectively connecting the control of each printing head to be controlled with one of the contacts in one of the grooves, a shaft driven by the machine, a sprocket for driving said chain, a ratchet associated with the sprocket, a crank on said shaft, and a lost motion connection between the crank and the ratchet.

24. The combination with a block printing machine, of a selector mechanism for controlling the sequence of movement of the printing heads of the printing machine, said selector including a carrier having a succession of independently adjustable contact elements thereon, and means operated by the printing machine for intermittently advancing the carrier, said means including a lost motion connection.

25. The combination with a block printing machine, of a selector mechanism for controlling the sequence of movement of the printing heads of the printing machine, said selector including a carrier having a succession of independently adjustable contact elements thereon, means operated by the printing machine for intermittently advancing the carrier, said means including a lost motion connection, and a master controller operated synchronously with the carrier.

26. The combination with a block printing machine, having a plurality of printing heads, of a selector including a carrier having a plurality of transversely movable contact elements thereon, said selector having fixed contact elements in the path of movement of the contact elements on the carrier, and a master controller for arranging the contact elements of the carrier in the desired transverse positions according to a predetermined sequence.

27. The combination with a block printing machine, having a plurality of printing heads, of a selector including a carrier having a plurality of transversely movable contact elements thereon, said selector having fixed contact members in the path of movement of the contact elements on the carrier, and a master controller for arranging the contact elements of the carrier in the desired transverse positions according to a predeter-

mined sequence, said master controller including a second endless carrier having adjustably fixed stop members thereon.

28. The combination with a block printing machine, having a plurality of printing heads, of a selector including a carrier having a plurality of transversely movable contact elements thereon, said selector having fixed contact members in the path of movement of the contact elements on the carrier, a master controller for arranging the contact elements of the carrier in the desired transverse positions according to a predetermined sequence, said master controller including a second endless carrier having adjustably fixed stop members thereon successively positioned to correspond to the desired sequence of setting of the contact elements on said first carrier, means for operating both carriers in synchronism, opposed contact moving blocks adapted to effect transverse movement of the contact elements on said first carrier, the stop members on said second carrier being adapted to limit the movement of said contact moving blocks, and means for imparting the desired variable transverse movement to the blocks.

29. The combination with a block printing machine, having a plurality of printing heads, of a selector including a carrier having a plurality of transversely movable contact elements thereon, said selector having fixed contact members in the path of movement of the contact elements on the carrier, a master controller for arranging the contact elements of the carrier in the desired transverse positions according to a predetermined sequence, said master controller including a second endless carrier having adjustably fixed stop members thereon successively positioned to correspond to the desired sequence of setting of the contact elements on said first carrier, means for operating both carriers in synchronism, opposed contact moving blocks adapted to effect transverse movement of the contact elements on said first carrier, the stop members on said second carrier being adapted to limit the movement of said contact moving blocks, means for imparting the desired variable transverse movement to the blocks, and means for simultaneously rendering said second carrier and one of said blocks ineffective.

30. The combination with a block printing machine, having a plurality of printing heads to be controlled, each of which has an electric control therefor, of a selector for the control of each printing head to be controlled including an endless carrier having a plurality of transversely shiftable contact elements thereon, a pair of levers arranged transversely to the carrier, springs for urging the levers toward each other, means for spreading the levers, a pair of blocks slidably mounted across the path of travel of the car-

rier and adapted to successively engage the contact elements on the carrier to shift said contact elements transversely, one of said blocks being connected with one of said levers and the other of said blocks being connected with the other of said levers, means for limiting the movement of the blocks in predetermined sequence, and means for moving the carrier when said levers and blocks are spread to the widest limit of their movement.

31. The combination with a block printing machine, having a plurality of printing heads to be controlled, each of which has an electric control therefor, of a selector for the control of each printing head to be controlled including an endless carrier having a plurality of transversely shiftable contact elements thereon, a pair of levers arranged transversely to the carrier, springs for urging the levers toward each other, means for spreading the levers against the action of the springs, a pair of blocks slidably mounted across the path of travel of the carrier and adapted to successively engage the contact elements on the carrier to shift said contact elements transversely, one of said blocks being connected with one of said levers and the other of said blocks being connected with the other of said levers, means for limiting the sliding movement of the blocks, means for moving the carrier when said levers and blocks are spread to the widest limit of their movement, and means for selectively holding one of the blocks against operation.

32. The combination with a block printing machine, having a plurality of printing heads to be controlled, each of which has an electric control therefor, of a selector for the control of each printing head to be controlled including an endless carrier having a plurality of transversely shiftable contact elements thereon, a pair of levers arranged transversely to the carrier, springs for urging the levers toward each other, means for spreading the levers, a pair of blocks slidably mounted across the path of travel of the carrier and adapted to successively engage the contact elements on the carrier to shift said contact elements transversely, one of said blocks being connected with one of said levers and the other of said blocks being connected with the other of said levers, means for limiting the movement of the blocks in predetermined sequence, and means for moving the carrier when said levers and blocks are spread to the widest limit of their movement, said means for limiting the movement of the blocks comprising a second carrier having a succession of stop elements thereon each of which is transversely adjustable, and means for moving said second carrier synchronously with the first.

33. The combination with a block printing machine, having a plurality of printing heads to be controlled, each of which has an electric

control therefor, of a selector for the control of each printing head to be controlled including an endless carrier having a plurality of transversely shiftable contact elements thereon, a pair of levers arranged transversely to the carrier, springs for urging the levers toward each other, means for spreading the levers, a pair of blocks slidably mounted across the path of travel of the carrier and adapted to successively engage the contact elements on the carrier to shift said contact elements transversely, one of said blocks being connected with one of said levers and the other of said blocks being connected with the other of said levers, means for limiting the movement of the blocks in predetermined sequence, means for moving the carrier when said levers and blocks are spread to the widest limit of their movement, said means for limiting the movement of the blocks comprising a second carrier having a succession of stop elements thereon each of which is transversely adjustable, means for moving said second carrier synchronously with the first, and means for rendering said second carrier inoperative and for simultaneously locking one of said blocks against movement.

34. The combination with a block printing machine having a plurality of printing heads to be controlled, each of which has an electric control, of a selector mechanism for the controls of the printing heads to be controlled including a carrier having adjustable contacts thereon, means on the machine for driving the carrier, and a master controller for arranging the contacts on the carrier in a predetermined sequence.

35. The combination with a block printing machine having a plurality of printing heads to be controlled with an electric control for each head to be controlled, of a selector comprising an endless carrier, a support for the carrier, a plurality of rods in the carrier, a transversely movable contact element on each rod, a plurality of parallel guide ways in the support along which the contacts of said rods travel, the length of the guide ways being less than the length of the carrier whereby some of the contacts are always out of the guide ways, a succession of contacts in each guide way, there being one contact in each guide way for each printing head to be controlled, means for selectively connecting the electric control of each printing head with its corresponding contact in any one of said guide ways, and means for intermittently advancing the carrier.

36. The combination with a block printing machine having a plurality of printing heads to be controlled with an electric control for each head to be controlled, of a selector comprising an endless carrier of variable length, a support for the carrier, a plurality of rods in the carrier, a transversely movable contact element on each rod, a plurality of

parallel guide ways in the support along which the contacts of said rods travel, the length of the guide ways being less than the length of the carrier whereby some of the contacts are always out of the guide ways, a 79 succession of contacts in each guide way, there being one contact in each guide way for each printing head to be controlled, means for selectively connecting the electric control of each printing head to be controlled with its corresponding contact in any one of said 75 guide ways, and means for intermittently advancing the carrier.

37. The combination with a block printing machine having a plurality of printing heads to be controlled with an electric control for each head to be controlled, of a selector comprising an endless carrier, a support for the carrier, a plurality of rods in the carrier, a transversely movable contact element on each rod, a plurality of parallel guideways in the support along which the contacts of said rods travel, the length of the guide ways being less than the length of the carrier whereby some of the contacts are always out of the 90 guide ways, a succession of contacts in each guide way, there being one contact in each guide way for each printing head to be controlled, means for selectively connecting the electric control of each printing head to be controlled with its corresponding contact in any one of said 95 guide ways, means for intermittently advancing the carrier, and means operated by the printing machine for arranging the contacts on said carrier in a predetermined sequence.

38. The combination with a block printing machine having a plurality of printing heads to be controlled with an electric control for each head to be controlled, of a selector comprising an endless carrier, a support for the carrier, a plurality of rods in the carrier, a transversely movable contact element on each rod, a plurality of parallel guide ways in the support along which the contacts of said rods travel, the length of the guide ways being less than the length of the carrier whereby some of the contacts are always out of the guide ways, a succession of contacts in each guide way, there being one contact in each guide way for each printing head to be controlled, means for selectively connecting the electric control of each printing head to be controlled with its corresponding contact in any one of 105 said guide ways, means for intermittently advancing the carrier, means operated by the printing machine for arranging the contacts on said carrier in a predetermined sequence, and a control for rendering said last named means inoperative.

39. In a block printing machine, a plurality of printing heads to be controlled, a hold-out latch for each head to be controlled, movable into and out of locking position, a shaft on which the hold-out latch is carried, a 110

weighted lever on said shaft for normally urging it to latching position, mechanical means for lifting said weighted lever to effect movement of the latch to inoperative position, and an electro-magnetic means for rendering said mechanical means effective.

40. In a block printing machine having a plurality of reciprocable printing heads to be controlled, a hold-out latch for each head to be controlled movable into and out of operative position, mechanical means for effecting movement of the latch to one position, and electro-magnetic means for rendering said mechanical means effective.

41. In a block printing machine having a plurality of reciprocable printing heads to be controlled, a hold-out latch for each head to be controlled movable into and out of operative position, mechanical means for effecting movement of the latch to one position, electro-magnetic means for rendering said mechanical means effective, and a selector for energizing said electro-magnetic means at predetermined periods.

42. In a machine for printing floor covering having a plurality of printing heads to be controlled with means for reciprocating each head to be controlled and a common driving means for all of the heads to be controlled, a hold-out latch for each head to be controlled movable into and out of operative position, a shaft on which each latch is carried, a fixed lever on each shaft, a counterweighted lever pivotally connected to each of said fixed levers and adapted to urge the shaft in a direction which moves the latch to operative position, a drop link on each of said counterweighted levers, a reciprocable bar operated by the machine having a dog thereon for each printing head to be controlled, said dog being adapted to engage the respective drop links when they are held in elevated position, said dogs being adapted to ride past said drop links when they are dropped down, means on the bar for initially raising each of the drop links upon reciprocation of the bar in one direction and an independently controlled electro-magnet for each head to be controlled for holding the drop link in elevated position when said magnet is energized, and a selector for controlling the energization of the drop links, said dog having an inclined end adapted to hold the drop link away from said magnet to prevent the rubbing of the drop link on the magnet during the operation of the trip mechanism.

43. In a block printing machine, a plurality of printing heads to be controlled, a hold-out latch for each head to be controlled, a mechanical latch-operating mechanism, and an electrically-controlled trip mechanism for rendering the mechanical latch-operating mechanism effective to release the latch.

44. In a block printing machine, a plurality of printing heads to be controlled, a hold-out latch for each head to be controlled movable into and out of locking position, a common reciprocable power driven bar for operating the latch of each head to be controlled, and an electrically-operated means

for selectively transmitting motion from the bar to the head.

45. In a block printing machine, a plurality of printing head to be controlled, a hold-out latch for each head to be controlled movable into and out of locking position, a power driven latch-operating member, and an electrically-controlled drop link for selectively transmitting motion from the said member to the latch.

46. In a machine for printing floor covering having a plurality of printing heads to be controlled with means for reciprocating each head and a common driving means for all of the heads to be controlled, a hold-out latch for each head to be controlled movable into and out of operative position, a shaft on which each latch is carried, a fixed lever on each shaft, a counterweighted lever pivotally connected to each of said fixed levers and adapted to urge the shaft in a direction which moves the latch to operative position, a drop link on each of said counterweighted levers, a reciprocable bar operated by the machine having a dog thereon for each printing head to be controlled, said dog being adapted to engage the respective drop links when they are held in elevated position, said dogs being adapted to ride past said drop links when they are dropped down, means on the bar for initially raising each of the drop links upon reciprocation of the bar in one direction and an independently controlled electro-magnet for each head to be controlled for holding the drop link in elevated position when said magnet is energized, and a selector for controlling the energization of the drop links, said dog having an inclined end adapted to hold the drop link away from said magnet to prevent the rubbing of the drop link on the magnet during the operation of the trip mechanism.

47. In a block printing machine through which a strip of material is intermittently moved in sections of uniform length, a plurality of printing heads to be controlled, an electric control unit for each head to be controlled, a selector having various contacts to which the respective control units are selectively connected, a carrier cooperating with said contacts having a succession of independently adjustable contact elements thereon, the number of such contact elements exceeding the number of sections of material in the machine between the first and last printing heads thereof, said contact elements on the carrier being adapted to cooperate with said first contacts, and means for moving the carrier.

48. In a printing machine having a plurality of printing heads adapted to print upon material advancing through the machine, a selector for controlling the dropping of the printing heads upon the material, a master controller normally controlling the se-

lector, and means for preventing the control of the selector by the master controller.

49. In a block printing machine having a plurality of printing heads to be controlled and adapted to print upon material advancing through the machine, a latch for each head to be controlled which is normally operative to prevent operation of the head, an electro-magnet for each head to be controlled for releasing the latch, and a selector mechanism for controlling the electro-magnets comprising an endless carrier having a succession of contactors thereon, and a parallel series of ways along which the contactors may move, some of the ways having spaced contacts therealong and at least one of the ways having no contacts therealong.

50. In a printing machine having a plurality of printing heads to be controlled and adapted to print upon material advancing through the machine, a latch which is normally operative for holding each head to be controlled against operation, an electro-magnet for releasing each latch, and a selector for controlling the energization of said electro-magnets and capable of sequentially holding the heads inoperative as a section of material upon which no printing is desired passes through the machine.

51. The combination with a block printing machine having a plurality of printing heads, of a selector including a carrier having a plurality of transversely movable head control elements thereon, means for effecting such transverse movement, a plurality of stops for the last mentioned means arranged in a desired sequence, a means for moving the stops successively into position to be engaged by said means for effecting transverse movement.

52. The combination with a block printing machine having a plurality of printing heads, of a selector including a carrier having a plurality of transversely movable head control elements thereon, means for effecting such transverse movement, and a stop for the last mentioned means, the means for effecting such transverse movement being non-positive whereby such transverse movement may be stopped at any desired point without injury to the mechanism.

53. The combination with a block printing machine having a plurality of printing heads, of a selector including a carrier having a plurality of transversely movable head control elements thereon, oppositely disposed pushers adapted to effect said transverse movement, one being effective for moving a head control element in one direction and the other being effective for moving it in the other direction, and stop means for said pushers.

54. The combination with a block printing machine having a plurality of printing heads, of a selector including a carrier having a plurality of transversely movable head control

elements thereon, oppositely disposed pushers adapted to effect said transverse movement, one being effective for moving a head control element in one direction and the other being effective for moving it in the other direction, a plurality of stop means for said pushers arranged in a desired sequence, and means for moving the stops successively into position to be engaged by said pushers.

55. The combination with a block printing machine having a printing head, of a selector including a transversely movable head control element, non-positive means for effecting such transverse movement, and a stop for the non-positive means.

56. The combination with a block printing machine having a printing head, of a selector including a transversely movable head control element, and a pair of movable arms adapted to engage the head control element on opposite sides thereof.

57. The combination with a block printing machine having a printing head, of a selector including a transversely movable head control element, a pair of movable arms adapted to engage the head control element on opposite sides thereof, and stop means for said arms.

58. The combination with a block printing machine having a printing head, of a selector including a transversely movable head control element, a pair of movable arms adapted to engage the head control element on opposite sides thereof, positive means for spreading the arms, and non-positive means for causing the arms to move together.

59. The combination with a block printing machine having a printing head, of a selector including a transversely movable head control element, a pair of movable arms adapted to engage the head control element on opposite sides thereof, positive means for spreading the arms, non-positive means for causing the arms to move together, and a stop for the arms.

60. The combination with a block printing machine having a plurality of printing heads, of a selector including a transversely movable head control element, cooperating head control elements operatively connected to the several heads to be controlled and lying in different paths, there being different paths for different heads to be controlled, and means for positioning said transversely movable head control element so that it will travel in any desired one of said paths.

In testimony whereof I have hereunto set my hand.

DANIEL S. HOLT.
